UNITED STATES PATENT OFFICE.

MAX STARK, OF NEW YORK, N. Y.

CONTAINER OF THE ENVELOPE VARIETY.

1,405,636.

Specification of Letters Patent. Patented Feb. 7, 1922.

Application filed September 28, 1921. Serial No. 503,977.

To all whom it may concern:

Be it known that I, MAX STARK, a citizen of the United States, residing in New York city, in the county of New York, State of New York, have invented new and useful Improvements in Containers of the Envelope Variety, of which the following is a specification.

This invention relates to paper containers and particularly to such containers of the envelope variety and resides in providing a novel and efficient structural combination of said parts with closure means therefor. It further resides in the construction of paper containers having metallic fastening means between the cover and body thereof, so as to insure durable and lasting construction and at the same time obtain an efficient, sightly and inexpensive article.

20 The invention further resides in providing a container of the envelope variety suitable for holding papers, collector's papers, photographs, and also provides a sanitary container for linen articles such as napkins and 25 the like and particularly containers requiring repeated opening and closing of the fastening means.

The invention further resides in novel construction insuring durable and lasting qualities to such articles when made of such frail body material as paper when undergoing repeated use.

Further modification also permits its use as an ordinary mailing article capable of use 35 as an ordinary envelope without the necessary adhesives, providing sufficient fastening means therefor, allowing sealing against tampering and at the same time providing a construction permitting its repeated use.

40 Further novelty of the invention will be apparent by reference to the accompanying drawing forming a part of the specification and the invention particularly set forth by the appended claims.

45 In the drawing Fig. 1. is a rear elevation of the container. Fig. 2. is a view taken on the line 2—2 of Fig. 1. Fig. 3. is the same as Fig. 2. showing a partial operation in opening. Fig. 4. is a view showing a modified 50 construction of the rear of the body portion. Fig. 5. is an enlargement of the fastening device in open position.

55 Referring more particularly to the views in which A is the envelope proper formed by cutting the same from a one piece template with frontface 1 bent at the lower edge 2 up-

wards, to form rear face 3 and folded at the top edge 4 and extending downwards to overlap the face 3 to form the closure flap 5. The separate members of the snap fastener 60 6 pass through the rear face 3 and flap 5 respectively coordinating to form the proper fastening.

Referring to Fig. 5, particularly, the male or spring-ball head member 8 passes through rear face 3 and is upset at the inner portion 9 over the reinforcing and protecting and resilient paper washer 10 and is made secure on the outer face by upsetting the portion 11 over the metallic washer 12. The female 70 member or socket 13 is secured to the flap 5 and has the enlarged button 14 abutting on the flap 5, the neck 15 passes through the reinforcing strip 16, and extends beyond edge 17 of flap 5 to form a manipulating 75 handle 18. The mouth 19 is upset over the washer 20 securing the socket member firmly upon the flap.

In use with an article of the nature described, the snap fastener provides effective 80 securing means and at the same time permits speedy access and repeated use. As a paper container the particular arrangement of parts and construction insures extended life and durability with a body material so frail 85 as paper. Frequent manipulation in closing and opening of the container or envelope will ordinarily result in considerable tension upon the material 5, due to the resistance to separation of the socket member 13 from 90 the spring ball head 8. But for the construction shown very few applications of force upon the flap 17 itself where the body material is made of frail material will soon 95 tear the socket member from the flap.

By the construction shown, in effecting an opening, the flap 18 is grasped and pulled. Direct straight line tension is thereby effected only in the reinforcing and manipulating portion 16 and 18. The body material surrounding the socket member is submitted to nothing more than a compressive force, no other union between 5 and the strip 16 being effected than results from upsetting of the neck portion, thus permitting 105 free motion between the layers during the bending when tension is applied to the flap 18 (see Fig. 3).

Extending the handle strip beyond the edge 17 of the flap 5 insures the application of 110 force at the proper point and also offers increased friction when the thumb is forced

between the body and the flap in opening the same.

This extended strip has further novel utility as will be now described.

- 5 Referring particularly to Fig. 4, the rear face is made up by extending the turned flaps 3^b at the sides of the container and forming them into triangular portions extending beyond the center and forming lapped portions 10 3—3^b. Only ordinary adhesive or no adhesive at all need be used. The male or spring ball member 8 of the snap fastener passes through all three triangular flaps forming the inner face of the container where the 15 three corners overlap, and serving to securely rivet the parts together. The female portion or socket member is located in the fourth triangular turned down leaf forming the flap, at such a point as to properly coordinate with the male portion of the fastener in the body, the flap being similarly constructed with the extended strip and handle portion as above described.

With this construction the article can be 20 used for a container where sealing is desirable, or when the snap fastener has been closed, sealing wax S is poured over the extending member 18 and onto the body 3. After hardening the single seal serves to effectually prevent tampering as there are no glued edges to be steamed open, the body being secured by the single rivet and the flap closed by the clasp and seal. Tampering of the contents can not be effected without 25 destruction of the envelope or breaking of the single seal. After having served this purpose, the breaking of the seal leaves an article to be used again or for uses for which the first mentioned container was intended 30 to be used.

The article can be made from a variety of sheeted material such as leather, cloth, or paper. I prefer however to make the same of paper of varied types, so called vulcanized 45 fibre, manila, or that resembling and having a linen or textile finish impressed or embossed thereon.

Although I have described only a single fastener for the container I may use as many 50 fasteners as the size and shape of the envelope container requires to supply the necessary closing means and although I have claimed a single fastener, the novel construction embodying the fastener equally applies wherever a plurality of said fastening means are employed.

What I claim and desire to secure by Letters Patent is as follows:

1. In combination with a container of the 60 envelope variety having turned sides forming the rear face and closing flap, a metallic snap fastener serving as closing means between said rear face and said flap, one member of said fastener being attached to the rear face of said envelope, the other member

of said fastener being attached to the flap, and means attached to said last named member of said fastening means taking substantially all the tension due to resistance in separating said members of the fastener.

2. In combination with a container of the envelope variety having turned sides forming the rear face and closing flap, a metallic snap fastener serving as closing means between said rear face and said flap, one member of said fastener passing through all the sides forming the rear face and attached thereto, the other member of said fastener being attached to the flap and means attached to said last named member 75 of said fastening means serving as an operating handle and taking substantially all the tension due to resistance in separating the members of the fastener.

3. In combination with a container of the envelope variety having a rear face and closing flap, a metallic snap fastener serving as closing means therefor, the male portion of said fastener passing through and attached to the rear face of the envelope, the female portion passing through near the edge of the flap forming the closure member of said envelope, a reinforcing strip through which the neck portion of said female portion of the fastener passes and 90 attached thereto by upsetting the neck portion of said female portion, said reinforcing strip extending substantially beyond the edge of the flap to form a handle portion.

4. In combination with a container of the envelope variety having turned sides forming the rear face and closing flap, a metallic snap forming fastener serving as closing means between said rear face and said flap, one member of said fastener passing 100 through all the sides forming the rear face and attached thereto, the other member of said fastener being attached to the flap near the edge thereof, a reinforcing strip between said flap and the attaching means of 105 the fastening member, said reinforcing strip extending beyond the edge of the flap to form an operating portion.

5. In combination with a container of the envelope variety having a rear face and closing flap, a metallic snap fastener serving as the closing means therefor, reinforcing means comprising a resilient paper washer and an extended strip, the male member of the fastener passing through the rear face 110 of the envelope and the resilient paper washer, and attached by upsetting the shank thereof, said shank being upset over said resilient washer; the female member passing through the flap of the envelope and the extended reinforcing strip and adapted to contact with the male portion of the fastener to close the same, the neck of the female portion passing through the flap and the extended reinforcing strip and attached there- 115 120 125 130

to only by upsetting the neck over said reinforcing strip, said strip serving as an operating portion in opening the envelope.

6. In combination with a container of the
5 envelope variety having a rear face and closure flap, a metallic snap fastener serving as the closing means therefor; reinforcing means comprising a resilient paper washer and extended strip, the male member of the
10 fastener passing through the rear face of the envelope and the resilient paper washer and attached by upsetting the shank thereof, said shank being upset over said resilient washer; the female member passing through
15 the flap of the envelope and adapted to contact with the male portion of the fastener to close the same, the neck of the female portion passing through the flap and the extended reinforcing strip passing beyond the
20 edge of the flap serving as an operating handle and taking substantially the full tension when the members of the fasteners are separated.

7. A paper envelope to be used for repeated opening and closing having the usual
25 flap, provided with a snap fastener as

closure means between the flap and the body of the envelope, said flap provided with reinforcing and opening means for said fastener, said means eliminating substantially 30 all the tension in the flap when using the same as an operating member between the flap and the fastener member in the flap.

8. A paper envelope to be used for repeated opening and closing having the usual 35 flap, and provided with a snap fastener near the edge of the flap, the member of the fastener on the flap being provided with reinforcing means for said member, said reinforcing means being extended sufficiently to 40 form an operating handle portion.

9. A paper envelope to be used for repeated opening and closing having the usual flap, and provided with a snap fastener near the edge of the flap, the member of the 45 fastener on the flap being provided with reinforcing means for said member, said reinforcing means extending beyond the edge of the flap and thereby providing an operating handle portion.

MAX STARK.
